UNITED STATES PATENT OFFICE

LOUIS C. KUEHNER, OF ST. LOUIS, MISSOURI, ASSIGNOR TO HANDLAN-BUCK MANUFACTURING COMPANY, OF ST. LOUIS, MISSOURI, A CORPORATION OF MISSOURI

LAMP HOUSING

Application filed August 19, 1929. Serial No. 386,763.

This invention relates generally to lamps, and particularly to signal lamps of the type used on railroads and in other connections where signal lamps of this type are employed, the predominant object of the invention being to provide a signal lamp which is so constructed that the manufacture thereof is very greatly simplified, with the realization of a corresponding saving in the cost of such manufacture.

10 In the operation of railroad systems a great variety of lamps for signaling and other purposes is employed, and prior to this invention it has been necessary for manufacturers of such lamps to maintain stocks of different lamp housings on hand for the manufacture of said lamps. For instance, lamps intended for use on railroads are made which are provided either with one, two, or four lenses, and heretofore it has been necessary for the manufacturers of these lamps to be supplied with a stock of lamp housings employed in making lamps of each variety.

15 The necessity for the maintenance of stocks of lamp housings of different varieties, together with the inconvenience incident to the absence of standardization in connection with lamp housings, has been a source of expense to lamp manufacturers, and I have therefore devised the lamp housing disclosed herein, which, briefly stated, involves providing a plurality of lamp housing parts from which any one of a number of varieties of lamp housings may be constructed. By 20 this arrangement it is necessary merely that the lamp manufacturer be supplied with a stock of lamp housing parts of but two types, and from these lamp housing parts lamps of the one, two, or four lens type may be readily constructed. This entirely eliminates the necessity for the maintenance on hand of stocks of lamp housings of a number of different types, and as a result the manufacture of lamp housings is simplified and the cost 25 of such manufacture reduced.

25 Fig. 1 is a side elevation of a lamp housing of the one lens type constructed in accordance with this invention.

30 Fig. 2 is a cross-section on line 2—2 of Fig. 1.

Fig. 3 is a cross-section through a lamp housing of the two lens type.

Fig. 4 is a cross-section through a lamp housing of the four lens type.

In the drawing, wherein is shown for the 55 purpose of illustration, merely, one embodiment of the invention, A designates my improved lamp housing which comprises a body portion B, a top C, and a base D. The top C and base D are of conventional design, any 60 suitable top and base being adapted for use as parts of lamp housings constructed in accordance with my invention, and said top C and the bottom wall E of the lamp housing to which the base D is attached being secured 65 in place as parts of the lamp housing in the usual manner.

The body portion B of the lamp housing A is constructed of a plurality of sections which are riveted or otherwise secured together to produce the complete body portion, there being employed, in the case of the lamp housing illustrated in Figs. 1 and 2, three sections 1 which may be referred to herein as blank sections, and which are duplicates of 70 each other, and one section 2 which has associated with it a goggle 3 with which a lens 4 is associated in the usual manner. Each of the sections 1 of the body portion B is provided along one edge thereof with a depressed portion 5, and in like manner the goggle section 2 is provided along one edge thereof with a depressed portion 6 (Fig. 2). At the edge of each section 1 and 2 of the body portion B, opposite to the depressed 75 edge portion thereof, said section is consistent with the remainder of the section other than the depressed portion thereof; that is to say, the depressed portion is present at one edge only of each of the sections 1 and 2. It 80 will be noted also by referring particularly to Fig. 2 that each of the sections 1 is an exact duplicate of the other sections 1, and therefore said sections are completely interchangeable with each other.

85 In constructing a lamp housing of the one lens type as illustrated in Figs. 1 and 2, three of the sections 1 are arranged with respect to each other so that the unvaried edge portion 90 7 of each section is seated in the depression 95 100 of

provided by the depressed portion 5 of the next adjacent section. Also, the section 2 is arranged in place, so that the depression provided by the depressed portion 6 thereof receives the unvaried edge portion 7 of the next adjacent section 1 at one side thereof, and with the unvaried edge portion 8 of said section 2 seated in the depression provided by the depressed portion 5 of the section 1 at the opposite side of said section 2. The adjacent sections 1 and 2 are then secured together in any suitable manner, as, for instance, by means of rivets 9, said rivets passing through the overlapping edge portions of the adjacent sections as shown in Fig. 2. When the sections 1 and 2 have been secured together as described to produce the body portion B, the lamp housing bottom wall E, with the base D attached thereto, and the top C are secured in place in the usual manner, and the lamp housing is complete.

When it is desired to construct a two lens lamp housing, such as that illustrated in Fig. 3, in accordance with my invention, the method followed is exactly as has already been described in connection with the one lens type of lamp housing illustrated in Figs. 1 and 2, with the exception that instead of using one of the goggle sections 1 as in the construction shown in Fig. 2, two of these sections are employed, said goggle sections being designated by the reference character 2^a in Fig. 3. In the two lens type of housing the sections 2^a are associated with two sections 1^a, which correspond exactly with the sections 1 of the construction illustrated in Fig. 3, said sections 2^a being disposed opposite to each other in the lamp housing shown in Fig. 3 and the sections 1^a and 2^a being secured together in the manner already described in connection with the structure shown in Fig. 2.

When a lamp housing of the four lens type such as that illustrated in Fig. 4 is constructed in accordance with my invention, four goggle sections 2^b are employed, said goggle sections being exact duplicates of the goggle sections 2 and 2^a of the constructions illustrated in Figs. 2 and 3, respectively. The goggle sections 2^b are arranged relative to each other, as shown in Fig. 4, that is, with portions of adjacent sections disposed in overlapping relation, and said sections are secured together at said overlapping portions by rivets 9' or otherwise.

It is obvious, in view of the foregoing, that a number of different types of lamp housings may be constructed from a stock of lamp housing sections of only two varieties, and it is plain that a substantial saving in time and money will be realized in the use of my invention.

While I have described my invention as relating particularly to the manufacture of railroad signal lamps, I do not wish to be

limited to this type of lamp, as my invention is applicable to lamps of various other types and for other purposes.

I claim:

1. A lamp housing comprising a body portion formed of a plurality of sections extended longitudinally of the lamp housing, said sections being so constructed and arranged as to be interchangeable in the manufacture of lamp housings with other sections to produce lamp housings of different varieties, said construction and arrangement being embodied in overlapping portions formed on adjacent sections, and means at said overlapping portions for securing said sections together. 70

2. A lamp housing comprising a body portion formed of a plurality of sections extended longitudinally of the lamp housing, said sections being so constructed and arranged as to be interchangeable in the manufacture of lamp housings with other sections to produce lamp housings of different varieties, such construction and arrangement being embodied in overlapping portions formed on adjacent sections, and fastening means extended through said overlapping portions for securing said sections together. 75

3. A lamp housing comprising a body portion formed of a plurality of sections extended longitudinally of the lamp housing, said sections being so constructed and arranged as to be interchangeable in the manufacture of lamp housings with other sections to produce lamp housings of different varieties, such construction and arrangement being embodied in overlapping portions formed on adjacent sections, and rivets extended through said overlapping portions for securing said sections together. 80

In testimony that I claim the foregoing I hereunto affix my signature.

LOUIS C. KUEHNER.
